RESCUE B. PAGE, OF LOS ANGELES, CALIFORNIA.

STABILIZER FOR FOLDING BEDS.

Application filed October 29, 1923. Serial No. 671,385.

This invention relates to the manufacture of folding beds and is particularly applicable to folding beds supported on wheeled structures in such a manner that they may be moved about the room and when folded may be moved out of the way into closets or other receiving structures.

It is an object of the invention to provide in a metal folding bed of this character, a stabilizer for preventing the over-turning of the bed structure upon the person opening same and for counter-balancing the bed structure in such a manner that it will remain in any position intermediate of the closed and opened position thereof and may be raised and lowered with the expenditure of very little effort. With the ordinary type of folding bed, in which springs are stretched between the bed frame and the carriage for the purpose of maintaining the bed in raised position, a carriage of considerable width must be employed, otherwise when it is attempted to lower the bed from vertical position, the carriage will tip up, often causing the bed to over-balance and fall upon the person operating same.

The invention employs as a stabilizer, a leg member pivoted to the bed frame at an intermediate point in such a manner that when the bed is lowered, the lower end of the leg will ride outwardly, and springs acting between the stabilizer leg and the bed frame in a manner to resist the outward movement of the stabilizer leg, thus instituting a resisting force against the weight of the bed frame as it swings downwardly from raised position.

It is an additional object of the invention to provide a foldable track leg for receiving and guiding the lower end of the stabilizer leg as it swings outwardly.

The especial advantages of the invention and further objects thereof will be made evident hereinafter.

Referring to the drawings which are for illustrative purposes only.

Fig. 1 is a side elevation of a bed incorporating the features of my invention, in raised position.

Fig. 2 is a fragmentary view showing the bed in lowered position.

Fig. 3 is a face view of the bed in raised position.

Fig. 4 is a fragmentary section taken on a plane represented by the line 4-4 of Fig. 3.

Fig. 5 is a fragmentary plan view corresponding to Fig. 4 showing the track member in lowered position.

A form of folding bed to which the invention is particularly adapted consists of a carriage 11 having wheels 12 and a bed frame 13 pivoted at 14, Figs. 1 and 3, on a cross bar 15 which extends between the end castings 18 of the carriage 11. The castings 18 of the carriage 11 are held together by the bar 15 and a lower bar 20 which may be hollow pipe or of solid material as desired. The bed frame 13 is comprised of side members 22 and end members 23 between which a spring fabric 24 is stretched. The particular structure is arranged to swing on the pivots 14 between the raised position shown in Fig. 1 and the lowered position shown in Fig. 2. Near the center of the bars 15 and 20, a pair of castings 25 are mounted as shown in the drawings, these castings supporting a hanger plate 27 which is of U shape, by the use of bolts 28 extending through the flanges 29 of the channel or U shaped member 27. On the bottom or web portion 31 of the member 27, a track member 32 is secured by screws 33, this track member consisting of a channel bar having the flanges thereof upwardly disposed and having a perpendicularly projected plate or toe 34 at the inner end thereof. When the bed frame 13 is in raised position, the track member 32 may be swung upwardly on the pivot bolts 28 into the position shown in Fig. 1. Spring members 35, Fig. 4, are attached by plates 36 to eccentrically disposed pins 37 so that the tension of the spring will be exerted above the pivots 28 when the track member is in raised position, thus holding it against falling, and will be exerted below the pivots 28 when the track member is in lowered position. Upon pivots 40, consisting of bolts or rivets as desired, situated at intermediate positions on the side bars of the bed frame, is a stabilizer leg 42 consisting of a flat bar bent into the bifurcated form shown in the drawing. As shown in Figs. 4 and 5, angle brackets 43 are riveted at 44 to the intermediate point of the leg 42 and have the purpose of supporting a shaft 45 upon which a wheel 46 is mounted. This wheel 46 is arranged to ride in the track 32 between the position shown in Fig. 1 and the position shown in Fig. 2. When the track 32 is in raised position as shown in Fig. 1, the wheel 46 rests on the plate 34 and the lower

100

105

110

end of the track member 32 extends upwardly across the forward edge of the wheel and serves as a lock against outward movement of the wheel and therefore a lock for preventing the bed from being over-turned. When it is desired to lower the bed from vertical position, the track 32 is swung downwardly into the position indicated in dotted lines 50, Fig. 1, or in full lines in Fig. 2, traction means consisting of a caster 51 preferably not at but near the outer end of said track and resting upon the floor then serving to support the said outward end of the track member 32.

15 It will be plainly evident that the bed may be wheeled about when the track member is lowered with the same ease as when the track member is in raised position owing to the wheel support 51. As the bed is 20 swung downwardly from the raised position, the wheel 46 moves outwardly in a direction of the arrow 60, Fig. 1, along the track 32, thus causing the stabilizing leg 42 to swing outwardly upon the pivots 40 25 against the action of tension springs 62 and 63 which extend between the head cross member 23 and links 65 secured through holes in the bifurcated ends of the leg 42. The resisting force exerted by the spring 30 62 and 63 against the outward swing of the stabilizing leg 42 increases proportionately with the outward movement of the member 42 which movement depends upon the downward swing of the bed frame 13, so that the 35 resisting force applied by the springs is proportionate to the downward force exerted by the weight of the bed frame in its various positions of unfoldment.

I claim as my invention:

- 40 1. In combination: a supporting structure; a bed frame pivoted on said structure; a stabilizer leg pivoted at an intermediate point to said bed frame; resilient means operative to resist the outward swing of said stabilizer leg; and a track arranged to receive the pressure of, and guide the lower end of said stabilizer leg, said track being foldable between upright position against said bed frame and laterally extended position.
- 45 2. In combination: a supporting structure; a bed frame pivoted on said structure; a stabilizer leg pivoted at an intermediate point to said bed frame; resilient means operative to resist the outward swing of said stabilizer leg; and a track arranged to receive the pressure of and guide the lower end of said stabilizer leg, said track being

foldable between upright position against said bed frame and laterally extended position; and traction means near the free end of said track for supporting the end of said track when said track is laterally extended.

60 3. In combination: a supporting structure; a bed frame pivoted on said structure; a stabilizer leg pivoted at an intermediate point to said bed frame; resilient means operative to resist the outward swing of said stabilizer leg; and a track arranged to receive the pressure of and guide the lower end 65 of said stabilizer leg, said track being foldable between retracted position within the vertically projected area of said supporting structure and laterally extended position; and traction means for supporting the end 70 of said track when said track is laterally extended.

75 4. In combination: a supporting structure; a bed frame pivoted on said structure; a stabilizer leg pivoted at an intermediate point to said bed frame; resilient means operative to resist the outward swing of said stabilizer leg; and a track arranged to receive the pressure of and guide the lower end 80 of said stabilizer leg, said track being foldable between retracted position within the vertically projected area of said supporting structure and laterally extended position; and traction means for supporting the end 85 of said track when said track is laterally extended.

90 5. In combination: a supporting structure; a bed frame pivoted on said structure; a stabilizer leg pivoted at an intermediate point to said bed frame; resilient means operative to resist the outward swing of said stabilizer leg; and a track arranged to receive the pressure of and guide the lower end 95 of said stabilizer leg, said track being foldable between retracted position within the vertically projected area of said supporting structure and laterally extended position; and traction means for supporting the end 100 of said track when said track is laterally extended.

105 110 In testimony whereof, I have hereunto set my hand at Los Angeles, California, this 20th day of October, 1923.
